Primary Examiner — Mary Ann Calabrese*Assistant Examiner* — Katalin G Kloberg(74) *Attorney, Agent, or Firm* — Woodard, Emhardt, Henry, Reeves & Wagner, LLP(57) **CLAIM**

The ornamental design for a furniture, as shown and described.

DESCRIPTION

FIG. 1 is a top, front, right side perspective view of a furniture, showing my new design;

FIG. 2 is a top, front, left side perspective view thereof;

FIG. 3 is a top, rear, right side perspective view thereof;

FIG. 4 is a front elevation view thereof;

FIG. 5 is a right side elevation view thereof;

FIG. 6 is a top plan view thereof; and,

FIG. 7 is a cross-section view thereof taken along line 7-7 in FIG. 4.

The broken lines depict portions of the article that form no part of the claimed design.

1 Claim, 7 Drawing Sheets(56)
